Augustus Conradt

United States Patent Office.

AUGUSTUS CONRADT, OF PHILADELPHIA, PENNSYLVANIA.

Design No. 3,084, dated June 30, 1868.

DESIGN FOR THE HANDLES OF SPOONS OR FORKS.

The Schedule referred to in these Letters Patent and making part of the same.

TO ALL WHOM IT MAY CONCERN:

Be it known that I, AUGUSTUS CONRADT, of the city of Philadelphia, in the State of Pennsylvania, have invented a new Design for a Handle for Spoons, Forks, Knives, &c., and other articles of table use, which, to the best of my knowledge and belief, has not been known or used previous to this my application for Letters Patent for the said design. I do hereby declare that the following is a correct and exact description of the same, reference being had to the annexed drawing, and to the letters of reference marked thereon.

The nature of my invention is a new design for a shank for spoons, forks, &c.

A shank, commonly so called, is the centre part of a handle for such articles as mentioned above. From letters A to B this shank is tapering in its form, as shown in the drawing.

Having thus fully described the nature of my invention, I pray that the Commissioner of Patents may grant me a patent or exclusive right in the said design, for the purpose set forth and described in this petition.

What I claim as my invention, and desire to secure by Letters Patent, is—

The ornamental design of a tapering shank for the handle of a spoon, &c., as described and shown.

AUGUSTUS CONRADT.
